UNITED STATES PATENT OFFICE

JACOB M. SCHAFFER, OF WASHINGTON, DISTRICT OF COLUMBIA

ANTISEPTIC AND GERMICIDAL PRODUCT

No Drawing. Application filed October 20, 1928. Serial No. 313,927.

(GRANTED UNDER THE ACT OF MARCH 3, 1883, AS AMENDED APRIL 30, 1928; 370 O. G. 757)

This application is made under the act approved April 30, 1928, and the invention herein described, may be manufactured and used by or for the Government for governmental purposes without payment to me of any royalty thereon. I hereby dedicate the invention herein described to the free use of the public, to take effect upon the grant of a patent to me.

10 My invention relates to amyl phenols and hexyl phenols, and mixtures thereof, which are useful as antiseptics and germicides.

The invention includes substances above mentioned in a pure as well as in an impure 15 state.

My amyl phenols include those having the general formula $C_6H_{11}C_6H_4OH$. My hexyl phenols include those represented by the general formula $C_6H_{13}C_6H_4OH$.

20 My alkyl phenols may be prepared by any of the well known methods for making alkyl phenols. Several of the conventional methods that may be employed in making my alkyl phenols are disclosed in United States Patent 25 No. 252,782, issued January 24, 1882, to Adolph Liebmann, and in an article of applicant and F. W. Tilley, published in the Journal of Bacteriology of October, 1927.

My alkyl phenols may be emulsified or dissolved 30 in water or other suitable vehicle and then used as antiseptic and germicides.

I claim:

1. As antiseptic and germicidal products, amyl phenols.
- 35 2. As antiseptic and germicidal products, hexyl phenols.
3. As antiseptics and germicides, normal amyl phenols.
4. As antiseptics and germicides, normal hexyl phenols.
- 40 5. As an antiseptic and germicidal product, para normal amyl phenol.
6. As an antiseptic and germicidal product, para normal hexyl phenol.

45 JACOB M. SCHAFFER.
